UNITED STATES PATENT OFFICE

151,477

DESIGN FOR A SPECTACLE CASE

George Swikart, Yonkers, N. Y., assignor to Plastal Corporation, New York, N. Y., a corporation of New York

Application May 8, 1947, Serial No. 138,908

Term of patent 7 years

(Cl. D57—1)

To all whom it may concern:

Be it known that I, George Swikart, a citizen of the United States, residing at Yonkers, county of Westchester, State of New York, have invented a new, original, and ornamental Design for Spectacle Cases, of which the following is a specification, reference being had to the accompanying drawing, forming part thereof.

Fig. 1 is a top plan view of a spectacle case, showing my new design;

Fig. 2 is a front elevational view thereof;

Fig. 3 is a bottom plan view; and

Fig. 4 is an end elevational view.

I claim:

The ornamental design for a spectacle case, as shown.

GEORGE SWIKART.
